(57) **CLAIM**

The ornamental design for a circumferential wrap for applying cooling and compression, as shown and described.

DESCRIPTION

FIG. 1 is a perspective view of a circumferential wrap for applying cooling and compression showing our new design; FIG. 2 is a right side view thereof; FIG. 3 is a top view thereof; FIG. 4 is a left side view thereof; FIG. 5 is a bottom view thereof; FIG. 6 is a front view thereof; FIG. 7 is a back view thereof; FIG. 8 is a right view thereof; FIG. 9 is a top view thereof.

FIG. 10 is a right side view of a second embodiment of the circumferential wrap for applying cooling and compression; and,

FIG. 11 is a top view thereof.

FIGS. 10 and 11 have been broken away to show indeterminate length.

The broken lines shown in FIGS. 1, 10 and 11 are for illustrative purposes only and form no part of the claimed design.
